DES. 479

8-3-1852

Des. 479

Rufell Wheeler & Stephen A. Bailey of Utica N.Y.
Letters Patent No 479 Dated Aug 3. 1852

The schedule referred to in thes Letters Patent and making part of the same.

To all whom it may concern:

Be it known that we Rufell Wheeler and Stephen A Bailey of the city of Utica in the state of New York have invented and produced a new and original design for the plates of a cooking stove which we verily believe has not been known prior to its production by us and we hereby declare that the following is a full and exact description of the same hereby referring to the annexed drawing of a cooking stove the plates of which are of the said design and which drawing truly sketches and exhibits the said design.

The plate for the top of the stove is finished with rounded corners and a raised head in the manner indicated in the drawings; the doors have a raised centre, springing pyramidal from the surface which is parallel to the sides of the stove until the pyramid commences the lowering planes of the pyramid being recessed as indicated in the drawings and the centre of the plate being truncated from the pyramid and ornamented with reed work as indicated in the drawing. The front plate of the stove has the words "Wheeler & Bailey Utica N.Y. No" and the hearth "American Eagle air tight" in raised letters upon it. The legs of the stove are recessed fillet from which springs an ogee corner member ornamented with a figure as indicated in the drawing.

A is a view of a stove the plates of which are of our design.

2

Dec. 479

No 1 is a crop section of the moulding of the side plates

No 2 is a crop section of the top moulding

No 3 is a crop section of the bottom moulding

No 4 is a crop section of the moulding of side plate and door.

We do not claim the exclusive rights to the general construction of the stove, but what we do claim is the design and configuration of the ornaments and mouldings as described and set forth in the accompanying drawings
